UNITED STATES PATENT OFFICE

FRANK L. BAMFORD, OF DETROIT, MICHIGAN, ASSIGNOR TO C. M. HALL LAMP COMPANY, OF DETROIT, MICHIGAN, A CORPORATION OF MICHIGAN

LAMP

Application filed September 4, 1928. Serial No. 303,780.

This invention relates to lamps and has particular reference to a vehicle lamp.

An object of this invention is to provide means for anchoring an electrical conductor directly to the reflector of a lamp and for forming an electrical connection between the electrical conductor and the lamp bulb carried by the reflector.

A further object of this invention is to simplify the connection between the electrical conductor and the lamp bulb of the lamp and to produce a simple and efficient structure which may be economically manufactured on a commercial scale.

Other objects and advantages of this invention will become more apparent as the following description proceeds, particularly when reference is had to the accompanying drawings wherein:

Figure 1 is an elevational view, partly in section, of a vehicle lamp showing the invention applied to the same.

Figure 2 is a fragmentary perspective view of a portion of the reflector shown in Figure 1.

Figure 3 is a perspective view of the connecting clip shown in Figure 1.

Figure 4 is a fragmentary perspective view showing the clip locked on the reflector, and Figure 5 is a fragmentary rear elevational view of the lines shown in Figure 1.

Referring now particularly to the drawings wherein like reference characters designate corresponding parts throughout all views, 10 is a lamp casing, 11 a reflector within the lamp casing and 12 is an electrical conductor for supplying electric current to the lamp bulb 13. As illustrated, the casing 10 may be provided with an opening 14 through which the conductor 12 is adapted to enter the casing.

The reflector 11 is provided substantially centrally with an opening 20 and this opening is surrounded by a rearwardly extending flange designated generally by the reference character 21. The flange 21 serves a double purpose, being adapted to form a socket for receiving the lamp bulb 13 and being adapted further to form an anchorage

for securing the conductors 12 to the reflector 11.

As illustrated in Figure 2 of the drawings the flange 21 is of an uneven contour being provided with the extended portions 22 provided with bayonet slots 23 for receiving the pins 24 carried by the base of the lamp bulb 13. Adjacent the ends of the bayonet slots 23 the reflector 11 is provided with the cut-away portions 25 to permit the passage through the opening 20 of the pins 24 thus permitting a locking of the pins 24 in the bayonet slots 23. In addition to the extended portions 22, the flange 21 includes the relatively short portions 26 provided with the radially outwardly extending lugs 27 adapted to lock the anchorage clip to the reflector 11 in a manner hereinafter to be described. As illustrated, the lugs 27 may be formed by stamping out portions of the flange 21 and by bending these portions laterally.

In Figure 3, there is illustrated a clip designated generally by the reference character 30, this clip being adapted to be locked to the reflector 11 by the lugs 27. The clip 30 includes an annular portion 31 formed of resilient material and bowed as clearly illustrated in Figures 1 and 4 of the drawing, for a purpose hereinafter to be more fully described. The internal diameter of the annular portion 31 of the clip 30 is sufficiently great to permit the clip to be slipped over the flange 21 on the reflector 11 and in order to permit a passage of the portion 31 past the lugs 27, there are provided the diametrically opposed cut away portions 32 in the annular portion 31, through which the lugs 27 may pass. Thus when the cut away portions 32 are aligned with the lugs 27, the clip 30 may be slipped on the flange 21 to a position between the lugs 27 and the body of the reflector 11 after which the clip 30 may be rotated to move the cut away portions 32 out of alignment with the lugs 27, so that the lugs 27 will prevent an outward movement of the clip 30 away from the reflector 11.

In order to prevent a rotation of the clip on the flange 21 after the same has been positioned in back of the lugs 27, the annular portion 31 of the clip is provided with the

diametrically opposed pairs of fingers or ears 33. As illustrated in Figure 3 of the drawing, these ears may be stamped outwardly from the portion 31 of the clip and the ears of each pair are spaced apart sufficiently to permit the positioning therebetween of the lugs 27. By stamping the ears 33 from the portion 31 the ears form oppositely directed cam surfaces 34 over which the lugs 27 will slide relatively easily to positions between the ears 33:

As illustrated the ears 33 are formed in the high portions of the annular portion 31 so that the resiliency of the portion 31 will tend to hold the ears 33 in engagement with the lugs 27. In order therefore to release the lugs 27 from engagement with the ears 33, it is necessary to slightly flatten the clip 30 by a flexing movement of the same, whereby the ears 33 will be moved out of the path of travel of the lugs 27 to permit a rotation of the clip 30 to again align the cut away portions 32 with the lugs 27.

For rigidly securing the conductors 12 to the clip 30, the annular portion 31 of the clip is provided with the laterally extending lip 35 and the conductor is provided on its end with a metallic terminal 36 adapted to be secured to the lip 35 as at 37. The connection 37 may either be a screw connection or a rivet and the conductor 12 may be insulated from the lip 35 as by the insulated pads 38 and 39.

For forming an electrical connection between the conductors 12 and the bulb 13, there is provided a contact finger designated generally by the reference character 45. This contact finger comprises the body portion 46 adapted to be clamped between the terminal 36 and the insulation 39, whereby the same is electrically connected to the conductor 12. The body portion 46 of the finger 45 is bent upwardly as at 47 and then forwardly as at 48 to provide the extended portion 49 overlying the annular portion 31 of the clip 30. The finger 45 is formed of resilient metal whereby the end 49 will be resiliently held in contact with the contact 50 of the bulb 13 when the latter is locked in the socket by engagement of the pins 24 in the bayonet slots 23.

From the above it is believed that the manner in which the structure embodying the inventive idea functions, will be readily apparent. The conductor 12 is adapted to be secured to the clip 30 by virtue of the connection 37 which may be either a rivet or a small bolt. The conductor 12 will thus be electrically connected to the contact finger 45 and will be insulated from the annular portion 31 of the clip 30. The clip 30 may be positioned on the flange 21 and in back of the lugs 27 by first aligning the cut away portion 32 of the clip with the lugs 27 and then moving the clip 30 inwardly to the

desired position. When the clip 30 is in back of the lugs 27, it may be rotated to disalign the cut away portions 32 with the lugs 27 and to engage the lugs 27 between the ears 33. Thus the clip 30 will be rigidly locked on the flange 21 and may only be unlocked by a flexing movement and a substantial rotative movement to disengage the lugs 27 from the ears 33 and to then align the lugs 27 with the cut away portions 32. The extension 49 of the contact finger 45 overlying the opening 20 will be in a position to engage the contact 50 on the bulb 13 and the resiliency of the finger 45 will tend to hold its extension 49 in engagement with the contact 50. Thus the conductor 12 will be firmly locked to the reflector 11, while an electrical connection will be formed between the conductor 12 and the lamp bulb 13.

While one form of the inventive idea has been disclosed with considerable detail, it is to be clearly understood that the description is for the purposes of illustration only. The right is therefore reserved to make such changes in the details of construction and arrangement of parts as will fall within the purview of the attached claims.

What I claim as my invention is:

1. In a vehicle lamp, a reflector having a rearwardly extending flange, a clip sleeved upon the flange for anchoring an electrical conductor to said reflector, and means projecting laterally from the flange for holding the clip thereon.

2. In a vehicle lamp, a reflector having an opening, a flange formed on said reflector around said opening, said flange forming a socket for receiving a lamp bulb, and a clip for anchoring an electrical conductor to said reflector, said clip being adapted for detachable locking engagement with said flange.

3. In a vehicle lamp, a reflector having a socket for receiving a lamp bulb, and a clip for anchoring an electrical conductor to said socket, said clip comprising an annular member adapted to surround said socket and adapted to be locked thereto.

4. In a vehicle lamp, a reflector having an opening and a flange surrounding said opening, said flange forming a socket for receiving a lamp bulb, radially outwardly extending lugs formed on said flange, and a clip for anchoring an electrical conductor to said socket, said clip including an annular member adapted to be locked under said lugs.

5. In a vehicle lamp, a reflector having an opening and a flange surrounding said opening, said flange forming a socket for receiving a lamp bulb, radially outwardly extending lugs formed on said flange, and a clip for anchoring an electrical conductor to said socket, said clip including an annular member adapted to be locked under said lugs, said annular member having cut away portions

for receiving said lugs whereby said annular member may be positioned under said lugs.

6. In a vehicle lamp, a reflector having a flange forming a socket for receiving a lamp bulb, radially outwardly extending lugs carried by said flange, and a clip for anchoring an electrical conductor to said flange, said clip comprising an annular member having cut away portions for receiving said lugs whereby said annular member may be positioned on said flange beyond said lugs, said clip being adapted to be rotated on said flange to move said cut away portions out of alignment with said lugs, and means for locking said clip against rotation on said flange.

7. In a vehicle lamp, a reflector having a flange forming a socket for receiving a lamp bulb, radially outwardly extending lugs carried by said flange, and a clip for anchoring an electrical conductor to said flange, said clip comprising an annular member having cut away portions for receiving said lugs whereby said annular member may be positioned on said flange beyond said lugs, said clip being adapted to be rotated on said flange to move said cut away portions out of alignment with said lugs, and means for locking said clip against rotation on said flange, said means including ears struck from said annular member for engagement with said lugs.

8. In a vehicle lamp, a reflector having a flange forming a socket for receiving a lamp bulb, radially outwardly extending lugs carried by said flange, and a clip for anchoring an electrical conductor to said flange, said clip comprising an annular member having cut away portions for receiving said lugs whereby said annular member may be positioned on said flange beyond said lugs, said clip being adapted to be rotated on said flange to move said cut away portions out of alignment with said lugs, and means for locking said clip against rotation on said flange, said means including ears struck from said annular member for engagement with said lugs, said annular member being resilient and being bowed whereby the same may be flexed to move said ears out of engagement with said lugs.

9. In a vehicle lamp, a reflector having a socket for receiving a lamp bulb, and means for detachably securing an electrical conductor to said socket and for forming an electrical connection between the conductor and lamp bulb, said means comprising a clip sleeved on said socket, said clip and socket having portions adapted for interlocking engagement upon a predetermined rotative movement of said clip on said socket.

10. In a vehicle lamp, a reflector having a socket for receiving a lamp bulb, and means for detachably securing an electrical conductor to said socket and for forming an

electrical connection between the conductor and lamp bulb, said means including a clip detachably engageable with said socket and a resilient contact finger arranged diametrically of said clip for engagement with the lamp bulb.

11. In a vehicle lamp, the combination with a lamp socket for receiving a lamp bulb, and an electrical conductor, of a clip fixed to said conductor and detachably connected to said lamp socket for anchoring said conductor to said lamp socket and for forming an electrical connection between the electrical conductor and the lamp bulb.

12. In a vehicle lamp, a lamp socket, a lug formed on the outer periphery of said socket, and a clip adapted for locking engagement with said lug for anchoring an electrical conductor to said socket.

13. In a vehicle lamp, a lamp socket, lugs formed on the outer periphery of said socket, and a resilient clip surrounding said socket and adapted to be sprung under said lugs for anchoring an electrical conductor to said socket.

14. In a vehicle lamp, a reflector having an opening for receiving a portion of a lamp bulb and provided about the opening with a flange that forms a socket for receiving the portion aforesaid of the bulb, that forms a seat for an electrical conductor attaching clip, and that has means cooperating with the reflector for holding the clip seated on the flange.

15. In a vehicle lamp, a reflector having an opening for receiving a portion of a lamp bulb and provided about the opening with a flange constituting a seat for an electrical conductor attaching clip, having means for anchoring the portion aforesaid of the bulb in the opening, and having other means for holding the clip seated upon the flange.

16. In a vehicle lamp, a reflector having an opening for receiving a portion of a lamp bulb and provided about the opening with means for anchoring the bulb in the opening and having other means for anchoring an electrical terminal attaching clip upon the reflector adjacent the opening.

17. In a vehicle lamp, a reflector having an opening for receiving a portion of a lamp bulb and provided about the opening with means for embracing the portion aforesaid of the bulb, said means being provided with means for anchoring the portion of the bulb in the opening.

18. In a vehicle lamp, a reflector having a flange forming a socket for a portion of a lamp bulb, an electrical terminal attaching clip in the form of a ring sleeved upon the flange, and a lug projecting from the flange holding the ring thereon.

19. In a vehicle lamp, a reflector, and an electrical conductor attaching clip having a

ring portion detachably connected to the reflector, and a spring contact arm having a bulb engaging portion disposed substantially parallel to the ring portion at approximately the center thereof.

⁵ In testimony whereof I affix my signature.

FRANK L. BAMFORD.
